UNITED STATES PATENT OFFICE

DONALD S. BARROWS, OF ROCHESTER, NEW YORK, ASSIGNOR TO THE SYMINGTON COMPANY, OF NEW YORK, N. Y., A CORPORATION OF MARYLAND

STRIKING CASTING

Application filed January 20, 1926. Serial No. 82,499.

This invention relates to combined striking castings used in connection with draft gear for railway cars and, more particularly, to such a casting adapted for supporting a replaceable carrier block.

The principal object of my invention, generally considered, is the provision of a combined casting which is formed with portions serving, respectively, as a coupler stop or striking casting and a sill tie member or coupler carrier iron and provided with means for connecting the same with the associated center sills of a car, said carrier iron portion being formed for the application of a replaceable wear or carrier block.

An object of my invention is the provision of a combined casting formed with striking and carrier iron portions, the carrier iron portion being formed with a pocket or indentation in its top surface for receiving and holding in place a renewable carrier block whereby the carrier iron portion of the casting is prevented from receiving wear from the coupler.

Another object of my invention is the provision of a combined casting adapted for connection with the underframe of a car and formed with coupler striking and carrier iron portions, the casting adjacent said carrier iron portion being formed with an aperture through which a carrier block may be inserted transversely and positioned in place on the top of the carrier iron portion which is so constructed that said block is securely held in place.

A further object of my invention is the provision of a combined casting adapted for connection with the center sills of a car and formed with a coupler striking portion and a carrier iron portion, said carrier iron portion being formed with upstanding flanges or ribs extending along the same for holding in place an associated carrier block, the carrier block being preferably formed with a lug or lugs cooperating with or engaging under the corresponding portion or portions on the casting for securing said block in place, retaining means being provided, if desired, for preventing undesired removal or loss on said block, said

retaining means being adapted for extending through registering portions of the casting and block or for engaging corresponding portions of said members to secure the same together.

55

Other objects and advantages of the invention relating to the particular arrangement and combination of the various parts will become apparent as the description proceeds.

60

Referring to the drawings illustrating my invention, the scope whereof is defined by the appended claims:

Figure 1 is a plan view partially in horizontal section of a car underframe to which is connected a combined casting constructed in accordance with my invention, a swivel butt coupler, yoke, follower and associated keys being illustrated diagrammatically in combination therewith.

70

Figure 2 is a vertical central longitudinal section of the embodiment shown in Figure 1.

Figure 3 is an end view partially in section of the embodiment shown in the preceding figures.

75

Figure 4 is a transverse vertical sectional view corresponding to Figure 3 but showing a modification.

Figure 5 is a horizontal sectional view 80 on the line 5—5 of Figure 4.

Figure 6 is a transverse vertical sectional view corresponding to Figure 4 but showing a further modification of my invention.

Figure 7 is a longitudinal sectional view 85 on the line 7—7 of Figure 6, looking in the direction of the arrows.

Figure 8 is a horizontal sectional view on the line 8—8 of Figure 6.

Figure 9 is an end view corresponding to Figure 3 but showing a still further modification.

90

Figure 10 is a longitudinal sectional view on the line 10—10 of Figure 9, looking in the direction of the arrows.

95

Figure 11 is a horizontal sectional view on the line 11—11 of Figure 9.

Referring to the drawings in detail, like parts being designated by like reference characters, and first considering the em-

100

bodiment of my invention illustrated in Figures 1, 2 and 3, there is shown a combined casting 1 formed with a coupler striking portion 2, a coupler carrier iron portion 3, and rearwardly extending ear or web portions 4 preferably lying on the outside of and adjacent to web portions 5 of the center sills 6 of the car. The web portions 4 are preferably connected to the adjacent ends 10 of the center or draft sills 6 by a plurality of rivets 7 and are also preferably bifurcated or formed as upper and lower sections 8 and 9, respectively, leaving slots 10 therebetween, said slots preferably registering 15 with the slots 11 provided in the associated center sills 6 for the reception of a usual form of draft key 12.

For reinforcing the slotted portions of the center sill webs 5, the slotted portions of the 20 webs or ears 4 of the combined casting 1 are preferably formed with outwardly extending rib or flange portions 13. The slots 11 in the center sill webs preferably extend to the ends of said webs and the bifurcated 25 ends of said center sills are securely tied together by the aforescribed connection with the combined casting. The center sills may be additionally connected to the combined casting by forming the lower web portions 9 of said casting with outstanding flange portions 14 overlying the lower flanges 15 of the center sills and connected thereto by rivets 16.

For reinforcing the slots in the webs 5 of 25 the center sills beyond the webs or ears 4 of the combined casting 1, cheek plates 17 are preferably provided connected on the outside of the webs 5 of the center sills by a plurality of rivets 18. These cheek plates 17 are preferably formed with one or more slots 19 registering with the slots 11 in the center sill webs and framed or bordered by flange or rib portions 20, the outwardly extending sections of which correspond with 30 the flange portions 13 around the slotted portions of the webs 4 and serve as continuations thereof while the inwardly extending portion 21 engages the edges of the slotted portions 11 of the center sills and serve to 35 properly position the cheek plates and provide a greater bearing area for the front draft key 12 as well as for another draft key 22, if used.

The striking casting portion 2 of the combined casting 1 is preferably formed with an upright web portion 23 adapted for engagement with the horn of the coupler 24, illustrated diagrammatically by dot and dash lines, upon sufficient rearward motion 40 thereof, and a lower inwardly extending web portion 25 overlying the shank of the coupler 24. Extending from the upper edge of the web portion 23 and continued rearwardly below the sill cover plate 26 and end sill 45 27 is a shelf or web portion 28 which is

preferably connected to the cover plate 26 and the end sill 27 by means of rivets 29. For bracing the web portions 23, 25 and 28 together, longitudinally extending web portions 30 are preferably provided, the rear portions of which preferably taper and gradually merge into the web 28. Said web 28, forwardly of the center sills 6, preferably extends transversely beyond said center sills 6 and the overhanging portions 31 of which are preferably braced with respect to the web portions 4 by means of transversely extending substantially vertical rib or flange portions 32, preferably extending substantially the full height of the combined casting. These flange portions 32 are, in turn, braced to the web portions 4 by preferably triangular gusset portion 33 and the corresponding portions of the web 28.

Between the center sills and rearwardly of the ends thereof, the web 28 is narrowed in width so as to extend between said sills without intersecting the same and is positioned so that the top thereof is substantially flush with the tops of the sills. This construction makes it possible to firmly connect the end sill and center sills while providing for the secure connection between the combined casting 1, the cover plate 26 and the center sills 6. The narrowed portion of the web 28 is preferably extended for a substantial distance to underlie the end sill 27 and, as will be apparent from a consideration of Figure 2 particularly, it preferably extends beyond the ears or web portions 4 100 of the casting.

The coupler carrier iron portion 3 of the combined casting is preferably formed with a substantially horizontal web 34 and upright stiffening flanges 35 positioned on opposite sides of said web, the major portion of said flanges depending below said web 34 but the upper portions extending above said web, as illustrated particularly in Figure 2, so as to form ribs or flanges 36 with a depression or pocket 37 therebetween. Said pocket or depression 37 is adapted for receiving a carrier block or wear element 38 which is adapted for insertion in place through one of the transverse apertures 39 provided in the web portions 4 of the casting and, after insertion, is prevented from loss or undesired removal by the ribs 36 along the sides thereof and corresponding ribs 40 at the ends of said block which define the extreme ends of the pocket 37. In the present embodiment, it will be apparent that the carrier block 38 is retained in place by being seated on the web 34 and being prevented from displacement by the ribs 36 and 40, the weight of the said block and the coupler engaging the upper surface thereof being relied upon to prevent upward removal of said block from the pocket 37.

The carrier block 38 is preferably formed 120

with an upper web 41 and flanges depending along the sides thereof and joined at the ends by flanges 43 forming an inverted trough-shaped construction which is preferably but not necessarily a casting. The intermediate portions of the flanges 42 may be braced and connected together by a depending flange or web 44. The carrier iron portion 3 underlying the carrier block 38 may be similarly constructed, that is, in addition to the flanges 35, end flanges or webs 45 may be provided as continuations of the ribs 40 and a bracing web or flange 46 may be provided directly beneath the flange or web 44. It will be apparent that, when in operative position, the stem of the coupler 24 rests directly on the web 41 of the carrier block and the depending flanges 42, 43 and 44 of said coupler block rest directly on the web 34 of the carrier iron portion 3. On account of this construction, almost the entire wear from the coupler is taken upon the replaceable or renewable carrier block 38, which is relatively small and cheap, thereby protecting the relatively expensive combined casting 1 and greatly prolonging the life thereof.

The vertical edges of the opening 47 through the casting 1 for the reception of the stem of the coupler 24 are preferably reinforced by inwardly extending flanges 48. In accordance with usual practice, the stem of the coupler 24 and the forward portion of the yoke 49 are supported in proper position between the sills 6 by means of the key 12 extending through registering slots in the coupler and yoke and through the slots 10 in the combined casting, slots 19 in the cheek plates and the slots 11 in the center sills, as will be understood. The coupler 24 is illustrated as of the swivel butt type described and claimed in my co-pending application Serial No. 5,763 filed January 30, 1925, which matured into Patent No. 1,637,099 on July 26, 1927, in which the butt thereof has a greater vertical dimension than the shank, although, as is obvious, any desired type of coupler may be employed. The present construction, however, is admirably suited for a coupler of the swivel butt type because it is especially adapted for receiving a large amount of wear from said coupler. The second or rear key 22 likewise extends through the corresponding slots in the cheek plates, center sills, yoke and front follower 50, as will be understood.

Referring now particularly to the modification of my invention illustrated in Figures 4 and 5, the combined casting 1^a, illustrated fragmentarily, may be substantially identical in construction with the combined casting 1 of the previous embodiment except that only one aperture 39^a is provided for inserting the carrier block 38^a in place. In lieu of an aperture 39^a on the other side

of the casting 1^a, a smaller aperture 51 is provided, the upper limit of which is defined by a depending ledge portion 52 which overlies a lug portion 53 from the carrier block 38^a which extends outwardly through the aperture 51 when the carrier block 38^a is in place. If desired, the lug 53 is securely connected to the underlying outwardly extending flange 54 on the carrier portion 3^a by means of a cotter or other retaining means 55 which preferably extends through registering apertures 56 and 57 in the carrier block and carrier iron portion, respectively. The other end of the carrier block 38^a is also preferably provided with an outstanding lug portion 58 which extends under the corresponding web portion 4^a of the combined casting and limits the upward movement of the carrier block with respect to said combined casting, and may also facilitate handling said carrier block.

Referring now to the further modification of my invention, illustrated in Figures 6, 7 and 8, a combined casting 1^b is fragmentarily shown which may be substantially identical in construction with the casting 1 heretofore described but, as in the immediately preceding embodiment, the carrier block 38^b is adapted for insertion in place from only one side of the casting 1^b through an aperture 39^b. The web portion 4^b at the opposite end of the casting, instead of being apertured, is formed of a contour, as illustrated particularly in Figure 6, providing an inwardly extending lug or web portion 59 overlying a pocket 60. A corresponding outwardly extending flange or lip 61 is provided on the lower edge of the flange or web 43^b of the carrier block 38^b which lug, when the block 38^b is in place, extends into the pocket 60 and underlies the ledge or lug 59 for securing the carrier block and particularly one end thereof in place. The other end of said carrier block 38^b is preferably secured in place, in the present embodiment, by means of a cotter or other retaining device 62 extending through apertures 63 in the walls of the combined casting so as to be positioned directly over an outstanding lip or lug portion 64 on the lower edge of the flange or web portion 43^b on the carrier block 38^b at the opposite end from the lip 61.

Referring now to the still further modification of my invention, illustrated in Figures 9, 10 and 11, a combined casting 1^c is fragmentarily illustrated and the same may be substantially identical with that previously illustrated except as specifically described. As in the immediately preceding embodiment of my invention, the carrier block 38^c is inserted in place from one direction only through aperture 39^c and one end of the same is retained in place by a lip portion 61^c thereon engaging in pocket 60^c in the combined casting and underlying 130

lug portion 59^c formed thereon. Instead of the carrier block 38^c being formed with flanges depending from the edges of the upper web 41^c, one of said flanges 42^c is inset from the edge of the web 41^c and provided with an outstanding flange or rib 65 leaving an inset or channel-shape portion 66 which is of sufficient size for allowing the carrier block 38^c to pass the pair of lugs 67 arranged on the combined casting 1^c. It will be noted that the block 38^c must be elevated from its normal position to pass the lugs 67 and, after insertion in place, said lugs serve to prevent loss or undesired removal of said block as well as the lip 61^c thereon and the ledge 59^c on the combined casting. The end of the carrier block 38^c adjacent the lugs 67 is correspondingly formed with lugs 68 so that, when in place, a slot 69 is provided between the lugs 67 and 68 and a flat cotter or other retaining device 70 may be applied in said slot, as illustrated, and serves to lock the carrier block 38^c in place and prevent undesired removal thereof.

By virtue of the aforescribed construction, it will be apparent that I have devised a combined casting with an associated coupler carrier block, the parts being so constructed that the block is readily applied and removed so that the same may be replaced when worn thereby protecting the combined casting from wear and prolonging the life thereof to a great extent. The depth or vertical dimension of said block is preferably so great that the butt of the coupler illustrated is insertable or removable only upon removal of the block, whereby only the normal amount of clearance illustrated in Figure 2 is provided above the coupler stem after assembly.

Having now described my invention, what I claim is:

1. A combined casting comprising portions serving, respectively, as a striking casting and coupler carrier iron, said carrier iron portion comprising an upper web and depending flanges and formed on its upper face with marginal flanges and a carrier block seated on said upper face and secured in position between said marginal flanges, said casting being adapted to cooperate with a coupler whose butt portion has a greater vertical dimension than the shank portion thereof, said block having so great a vertical dimension that the butt of said coupler can pass between the striking casting and carrier iron portions only upon removal of the block.

2. A combined casting formed with portions serving, respectively, as a striking casting and coupler carrier iron, said carrier iron portion being formed with flanges along its upper surface and said casting being provided with a transverse aperture therein,

said aperture being adapted for receiving a carrier block and the flanges serving to provide a pocket for receiving said block on the carrier iron portion.

3. A combined casting comprising portions serving, respectively, as a striking casting and coupler carrier iron, said carrier iron portion being provided with a pocket in its upper face for receiving a carrier block and a ledge portion overlying the pocketed portion of the carrier iron, and a carrier block seated in said pocket and provided with a lug portion underlying said ledge portion of the casting for retaining the block in position.

4. A combined casting comprising portions serving, respectively as a striking casting and coupler carrier iron, said carrier iron portion having an upper web shaped to provide a pocket for receiving a carrier block, a carrier block positioned thereon, one of the connecting sides of said casting being apertured for receiving said block, and a retaining member engaging corresponding portions on the carrier iron and block for preventing undesired removal thereof.

5. A combined casting comprising portions serving, respectively, as a striking casting and coupler carrier iron, a carrier block positioned on the upper surface of said carrier iron and provided with an outwardly flanged portion, said casting being provided with a corresponding ledge portion extending over said flange for retaining the block in position.

6. A combined casting comprising portions serving, respectively, as a striking casting and coupler carrier iron, a carrier block positioned on the upper surface of said carrier iron and provided with an outwardly flanged portion, said casting being provided with a corresponding ledge portion extending over said flange for retaining the block in position and retaining means cooperating with corresponding portions of the casting and block for preventing undesired removal of said block.

7. In combination with the center sills of a car, a combined casting comprising portions serving, respectively, as a striking casting and coupler carrier iron, and provided with rearwardly extending ears connected with the webs of the center sills and a shelf portion over the carrier iron portion of the casting extending rearwardly beyond the ears and with its top surface substantially flush with the tops of the center sills, said carrier iron portion being formed with a pocket on its upper face and with a replaceable carrier block seated in said pocket and adapted for supporting an associated coupler.

8. In combination with the center sills of a car, a combined casting comprising portions serving, respectively, as a striking cast-

ing and coupler carrier iron and provided with rearwardly extending ears connected to the adjacent web portions of the center sills and bifurcated for receiving an associated draft key therebetween, said carrier iron portion being formed on its upper face with marginal ribs and a carrier block seated on said upper face and secured in position by means of said ribs, said casting being apertured above the level of the carrier iron portion for receiving the block when inserted endwise.

9. In combination with the center sills of a car, a combined casting comprising portions serving, respectively, as a striking casting and coupler carrier iron, and formed with extensions serving as the front portions of cheek plates, said extensions being connected to the adjacent web portions of the center sills, said carrier iron portion being formed with flanges along its upper surface and the walls of the casting adjacent said carrier iron portion being apertured for receiving a carrier block therethrough, the flanges on said carrier iron portion serving for retaining said block in place on the carrier iron portion.

10. In combination with the center sills of a car, an integral casting comprising portions serving, respectively, as a striking casting and coupler carrier iron, and provided with extensions serving as the forward portions of cheek plates and connected to the adjacent portions of the center sills, said carrier iron portion being provided with a pocket in its upper face for receiving a carrier block and a ledge portion overlying the pocketed portion of the carrier iron, and a carrier block seated in said pocket and provided with a lug portion underlying the ledge portion of the casting for retaining the block in position.

11. In combination with the center sills, cover plate therefor, and end sill of a car, an integral casting comprising portions serving, respectively, as a striking casting and coupler carrier iron, and provided with rearwardly extending ears connected with the adjacent portions of the center sills and a substantially horizontal shelf portion extending rearwardly from the striking casting portion, a portion of the shelf extending rearwardly between the sills and connected with the cover plate and end sill, said carrier iron portion being formed with a substantially horizontal web portion and upright flanges on either side thereof, said web portions being positioned below the upper edges of said flanges.

12. In combination with the center sills of a car, a combined casting comprising portions serving, respectively, as a striking casting and coupler carrier iron and provided with rearward extensions connected to said center sills, said carrier iron portion

being shaped on its upper surface for retaining a replaceable carrier block, a carrier block positioned thereon, a side of said casting being apertured for the lengthwise insertion of said block, and a retaining member engaging corresponding portions of the carrier iron and block for preventing undesired removal of said block.

13. A replaceable carrier block comprising an integral casting formed with an upper web bordered by depending flanges along the edges thereof, said web being adapted for supporting an associated coupler and the flanges for engaging the top surface of an associated carrier iron, and an extension on an end of said block adapted to underlie a cooperating shouldered portion of an associated supporting member for retaining it in position.

14. A replaceable carrier block comprising an upper web portion with flanges depending therefrom, a portion of said flanges being formed with an outwardly extending lug for engaging a corresponding portion of an associated carrier iron for retaining said block in position.

15. In combination with a coupler having a shank and a butt portion of greater overall height than said shank, a combined casting comprising portions serving, respectively, as a coupler stop and a sill tie member, said sill tie member being spaced below said coupler stop portion a distance greater than the overall height of the coupler butt, and a removable carrier block adapted to seat on said sill tie member with its top a distance below the coupler stop portion greater than the height of the shank but less than the overall height of the butt of said coupler, said casting being apertured to permit insertion of the block lengthwise into position.

16. In combination with a coupler having a shank and a butt portion of greater overall height than said shank, a combined member comprising portions serving, respectively, as a coupler stop and sill tie portion, the member being constructed for supporting a carrier block above said sill tie portion, and a removable carrier block supported by said member above said sill tie portion, the top of said block being so disposed that the coupler is held in substantially horizontal position and cannot be completely removed until said block has been removed, said block being formed with a portion thereof closely underlying an associated part of the casting for retaining the block in place.

17. A combined casting comprising portions serving, respectively, as a striking casting and coupler carrier iron, said carrier iron portion being spaced sufficiently from the striking casting portion for the reception of a vertically enlarged coupler butt, having an upper web and depending side portions, and being indented along its upper

- surface, and a replaceable carrier block inserted in said indented portion, said block being so constructed that when in place it provides normal clearance thereabove for the stem of an associated coupler but prevents removal or insertion of a vertically enlarged butt thereof.
18. A combined casting comprising portions serving, respectively, as a striking casting and coupler carrier iron connected by side portions, said carrier iron comprising a substantially horizontal web portion, and upright stiffening flanges extending between the sides of the casting on either side of said carrier iron, the upper edges of the end portions of said flanges curving upwardly and outwardly to merge into side portions and effect an increase in depth of said flanges, and a carrier block positioned on said web between said flanges and extending to a height such that sufficient clearance is allowed for the shank of a swivel butt coupler, complete removal of which is possible only upon removal of the block.
19. A combined casting comprising portions serving, respectively, as a striking casting and coupler carrier iron connected by sides and spaced to form a coupler-stem receiving opening, a carrier block positioned on the upper surface of said carrier iron and formed with a web portion normally extending through one of said sides beyond said opening, and a retaining device extending through said web portion and the adjacent part of the casting for securing the block in position, fixed with respect to the carrier iron.
20. In combination with a coupler having a shank and a butt portion of greater vertical dimension than said shank, a combined casting comprising portions serving, respectively, as a striking casting and a sill tie member, formed with rearwardly extending side portions adapted for connection with the webs of associated sills and formed with rearwardly opening slots adapting said portions to function as the forward parts of cheek plates, and a shelf portion adapted to underlie and be connected to an associated sill cover plate, said sill tie member being spaced below said striking casting a distance greater than the vertical dimension of the coupler butt, and a removable carrier block supported by said casting above said sill tie member with its top disposed so as to support the coupler shank in substantially horizontal position, said coupler being removable only upon removal of the block.

In testimony whereof I affix my signature.
DONALD S. BARROWS.
